United States Patent Office

Des. 203,953
Patented Mar. 1, 1966

203,953

PAPER TAPE TYPEWRITER

Eliot Noyes, New Canaan, Conn., assignor to International Business Machines Corporation, Armonk, N.Y., a corporation of New York

Filed Mar. 29, 1965, Ser. No. 84,473

Term of patent 14 years

(Cl. D64—11)

FIG. 1

FIG. 2

FIG. 1 is a front perspective view of a paper tape typewriter showing my new design; and

FIG. 2 is a rear perspective view thereof.

The bottom of the design is plain and unornamented.
I claim:

The ornamental design for a paper tape typewriter, substantially as shown and described.
